UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

PORTABLE STOVE.

Application filed November 26, 1923. Serial No. 676,935.

To all whom it may concern:

Be it known that I, WILLIAM J. FRISBIE, a citizen of the United States, and a resident of Chicago, in the county of Cook and State of Illinois, have invented certain new and useful Improvements in Portable Stoves, of which the following is a specification.

My invention relates to portable stoves to be used by campers or travelers and is of the type in which a liquid fuel such as hydro-carbon oil is used. For such use the stove must be as light, compact and small as possible, while still giving the required cooking space for the ordinary outdoor or camping purposes. Provision must also be made for convenient packing of the several stove parts into a container which adapts itself readily for traveling purposes or for packing in with other baggage. Provision must also be made for the ready arrangement of the parts when setting the stove up for use, and for adequately protecting the fuel tank from the heat of the burners.

The body of my improved stove structure is of sheet metal and rectangular so that after the parts are arranged therein it will form a convenient package which can be readily carried in a suitcase or other container, or when provided with a handle it can be carried like a suitcase. However, the main feature of my invention resides in the arrangement for accommodating the stove burners and fuel tank. Such burners and tank are combined in a unitary structure with the burner structure mounted on the tank so that the unitary structure can be laid on its side in the container when the stove is folded up, the bottom of the container having an opening through which the tank is projected when the stove is set up so as to bring the tank below the container bottom with the burners within the container side walls and above the bottom, a wall between the burners and the tank serving as a support for the unitary structure and also for closing the bottom opening when the stove is in use. This arrangement brings the tank below the container bottom where

it is out of the way and protected and best insulated from the heat of the burners.

The above and other features of my invention are disclosed in the structure shown on the accompanying drawing, in which—

Fig. 1 is a plan view of the container with the cover partly removed and showing the unitary stove structure arranged therein before the stove is set up;

Fig. 2 is a plan view of the container with the stove unitary structure removed and with the container bottom opening exposed to receive the stove structure in operative position;

Fig. 3 is a plan view showing the stove structure in operative position, and

Fig. 4 is a sectional view on plane 4—4, Fig. 3.

The stove container or supporting frame is preferably of sheet metal and rectangular, comprising the front and rear walls 10 and 11, the end walls 12 and 13, the bottom wall 14, and a cover 15 which may be separable or hinged to the container body. Leg structures 16 and 17 are in the form of wire bent to provide the U-shaped feet 18, the ends 19 at the upper ends of the leg structures being deflected and extending through the front and rear walls of the casing at the lower corners thereof so that the legs may be swung to open position to support the casing as shown in Fig. 4, or to be swung upwardly with the feet 18 against the top of the cover when the stove is folded and arranged for shipping or travel, as shown in Fig. 1.

In the bottom 14 of the container is the rectangular longitudinally extending opening 20 adjacent whose ends guide frames 21 and 22 are secured to the bottom, which frames form slideways for the ends of the closure plate 23 which covers and closes the opening 20 when the stove is assembled for shipping. The closure plate has a locking or latch bar 24 pivoted thereto intermediate its ends by a pin 25. When the plate 23 has been slid along the frames 21, 22 into position to close the opening 20 the bar 24 is swung into position transversely of the plate

and with its ends into latching engagement with the latch brackets 26 and 27 secured to the front and rear walls of the casing just above the casing bottom. When the stove 5 is to be set up the latch bar is rotated into parallelism with the plate and the plate is slid along its guide frames into position at one side of the opening 20, as shown in Fig. 2.

10 On the inner sides of the front and rear walls of the casing and just below the upper edge thereof are the ledges 28 and 29 for supporting the grid frame 30. The grid frame shown is of wire bent in zigzag fashion, the ends 31 extending through suitable openings in the end walls of the casing so that the grid may be swung into vertical position or into horizontal position to rest on the ledges when the stove is in use.

15 The stove structure or heating element comprises the burner structure B and the fuel tank T, the burner structure being parallel with and rigidly mounted on the side of the tank. The burner structure comprises the supply pipe 32 terminating in fittings 33 and 34 having at their top the bases 35 and 36 for the burner caps 37 and 38, which caps are of sheet metal and provided in their tops with gas outlets 39. Depending 20 from the fittings 33 and 34 are the seats 40 and 41 which are in register with the fittings 42 and 43 which saddle on the tank and are rigidly secured thereto, these fittings having the tops 44 and 45 between which and the 25 seats 40 and 41 is received the plate 46, rivets or screws 47 extending through the seats, plate and fitting tops so that the burner structure is rigidly mounted on the tank and the plate held in proper alignment.

30 35 Extending upwardly from the burner structure pipe 32 and then laterally and parallel with the pipe is the duct 48 which has the transversely extending air inlet tubes 49. Extending radially from the end of the tank and in communication therewith is the fuel supply pipe 50 which terminates at its other end in the fitting 51, between which fitting and the nozzle 52 extends the generator tube 53. The nozzle projects into the 40 ends of the duct 48, and through the fitting 51 and the generator tube and the nozzle extends the valve stem 53' whose conical inner end cooperates with a suitable outlet opening (not shown) in the nozzle 52 to control the outflow of gas all in the well known manner. A stuffing box 54 surrounds the valve stem at the outer end of the fitting 51 and prevents leakage of fuel. The stem terminates in a knurled disc or wheel 55 by which 45 the stem may be readily turned. The generator tube 53 extends diametrically across the top of the burner head 37 whose cap has the depression 56 into which fuel may be poured for priming the burner, the burning fuel rapidly heating the generator tube and fuel

therein to convert such fuel into gas, which gas is blown into the duct 48 to be there thoroughly mixed with air entering through the tubes 49 so that a rich combustion mixture will be delivered into the pipe 32 and to the burners to be there consumed. The pipe 32 is always open to the burner 37, the heat from this burner keeping the generator tube sufficiently hot for generating purposes after the priming fluid has been 70 burned. The other burner 38 may be connected into service as desired by means of a suitable valve (not shown) controlled by the L-shaped stem 57 extending axially with reference to the pipe 32.

75 The tank is provided with a suitable filler opening 58 which as shown is in the side of the tank and provided with a plug 59. Extending into the tank at its right end I have shown a pump 60 by means of which air may be forced into the tank for maintaining the proper pressure therein for the forced feed of the heating fluid to the generator tube, the flow being controlled by the valve on the 80 stem 53'.

85 The sides of the plate 46 between the stove structure and tank is such that it may cover the opening 20 in the container body when the stove is to be set up for use. When the stove is closed up for shipment the closure plate 23 is locked in position over the opening 20, and the stove structure comprising the burner structure and tank and the plate 46 lies on its side in the container as shown 90 in Fig. 1, the depth of the container being such as to readily accommodate the plate 46 when on edge. When it is desired to set up the stove the stove structure is removed and the closure plate 23 is released and slid to one side as shown in Fig. 2 to expose the 100 opening 20. The opening 20 is of a size to readily permit insertion therethrough of the tank, and the stove structure after being raised to vertical position is canted to permit insertion of the pump end of the tank 110 below the container bottom, whereafter the stove structure is lowered until the plate 46 rests on the container bottom parallel with the opening 20. The structure is then slid toward the left to bring the fuel supply pipe 50 through the slot 61 in the container bottom and into the end 62 of the supporting bracket 63 secured to the end wall of the container, the lower end of the fitting 51 then resting against the top of the bracket to assist in supporting the stove structure and holding it rigid, as shown in Fig. 4. In the adjacent side of the container is the opening 64 through which the controlling disc 55 of the valve stem 53' extends when the stove 115 structure is set up, and in the opposite end wall of the container the opening 65 through which the fingers may be inserted to control the valve stem 57 for the burner 38. The supporting plate 46 is also deflected down- 120

wardly at intervals to form abutments 66 which, when the plate is in place against the container bottom over the opening 20, abut against the edges around the opening to accurately align the supporting plate and hold it in position. In the container bottom are the air inlet openings 67, and in the closure plate 23 are similar openings 68 which register with the container bottom openings when the plate is pushed to one side so that the plate will not interfere with the flow of air into the container and to the burner flames.

After the stove structure has been securely seated in operative position the grid frame 15 is dropped into horizontal position against its supporting ledges and the stove is ready for use, the leg structures 16 and 17 resting on the ground to hold up the container with the tank sufficiently clearing the ground to be protected. After priming fuel has been burned in the cup 56 to heat the generator tube and generate gas the valve stem 53' is turned and the gas delivered into the mixing duct 48, the mixture being then burned 25 at the burner head 37, and also at the head 38 under control of the valve stem 57. The supporting plate 46 for the stove structure acts also as a shield for the tank, the plate being preferably imperforate, and the tank 30 will therefore be kept cool and at a safe temperature. Being below the container when the stove is in use the tank will be entirely out of the way and protected against 35 blows, bumps, etc., and when the pressure drops it can be readily restored by manipulating the pump 60.

When it is desired to pack up the stove the stem 53' is turned to close its valve and shut off the flow of fuel and then the stove 40 structure is shifted toward the right to bring the valve controlling wheel 55 within the container and the pipe 50 out of the fitting 63 and the slot 60. The structure is then canted and lifted to release the pump 45 end of the tank and to raise the tank up through the opening 20. The closure plate 23 is then slid into place over the opening 20 and locked by means of its latch bar 24, and the stove structure is then laid on its side in 50 the tank as shown in Fig. 1. The grid frame is then swung down against its supporting ledges and the cover 15 applied, whereafter the leg structures 16 and 17 are 55 swung against the top of the cover to lock it in place. The stove is then in compact form to be shipped or stored away. On the front wall of the stove a handle 69 is pivoted by means of which the stove can be readily carried.

60 The latch bar 24 may be provided with a knob 70 to facilitate its manipulation and the closure plate 23 may be provided with knobs 71 to facilitate its sliding back and forth in its guide frames 21 and 22 to expose 65 or to cover the opening 20.

The combination of the burner structure and tank in a rigid unitary structure with the permanent connection between the tank and the mixing chamber has many advantages. The generator tube is always rigidly held in proper realtionship to the burner heads and mixing tube and perfect operation is thus assured. There are no parts which could be forgotten or lost when the stove is packed up. When the stove is set 70 up the tank is entirely below the container bottom and shielded from the burner heat by the imperforate plate 46 which supports the stove structure in operative position. The entire stove is of simple, compact and durable construction and arrangement and does not take up any more floor space when set up for use, than when packed up for 75 shipment or travel. Changes and modifications can of course be made which would still come within the scope of my invention and I do not therefore desire to be limited to the precise construction and arrangement shown.

I claim as follows:

1. In a stove of the class described, the combination of a stove frame in the form of a casing, a stove structure comprising a burner element and a fuel tank permanently connected together, said structure being adapted when not in use to be received entirely within said casing, and means for supporting said structure in operative position with the burner element within the casing and the tank below the casing bottom.

2. In a stove of the class described, the combination of a stove frame in the form of a casing, a burner element, a fuel tank, means adapting said burner element and tank to be entirely received within said casing when the stove is not in use, means for supporting said burner element in operative position within said casing and said tank below the casing bottom when the stove is in use, and fuel supply connections between 100 said tank and burner element.

3. In a stove of the class described, the combination of a stove frame in the form of a casing, a burner element, a fuel tank, fuel supply connection between said tank and burner element, means adapting said burner element and said tank and supply connection to be entirely received within said casing when the stove is not in use, and means for supporting said burner element in operative position within said casing and said tank below the casing bottom when the stove is set up for use.

4. In a stove of the class described, the combination with a casing of a unitary stove structure, said structure comprising a burner element, a fuel tank, and a controllable fuel supply connection between said tank and burner element including a gas generator, said structure being adapted to be 125 130

entirely received within said casing when the stove is not in use, and means for supporting said structure in operative position with said burner element within the casing 5 and said tank below the casing bottom.

5. In a stove of the class described, the combination with a casing of a unitary stove structure, said structure comprising a fuel tank and a burner element together with a 10 fuel supply connection between the tank and burner element, said structure being adapted to be entirely received within said casing when the stove is not in use, said casing having an opening in its bottom permitting positioning of said structure in operative position with the burner element within the casing above said opening and the fuel tank below the opening, and a support for said structure forming a closure for said opening when the stove is in use.

6. In a stove of the class described, the combination with a stove frame in the form of a casing, of a unitary stove structure, said structure comprising a fuel tank, a 25 burner element, fuel supply connection between the tank and element, and a supporting plate between the tank and element, said casing having an opening in its bottom through which said tank may be lowered 30 when the stove is to be used, said plate then engaging with the casing bottom to close said opening and to form a heat insulating shield between the tank and burner element when the stove is in operation, said unitary 35 structure being adapted to be entirely received within said casing when the stove is not in use.

7. In a stove of the class described, the combination with a stove frame in the form 40 of a casing, of a unitary stove structure, said structure comprising a fuel tank, a burner element, and fuel supply connection between said tank and element, said structure being adapted to be entirely received within said 45 casing when the stove is not in use, the bottom of said casing having an opening permitting positioning of said structure in operative position with said burner element within the casing and above the opening and 50 with the tank below the opening, means for supporting said structure in such operative position, and a plate for closing said opening and for protecting said tank from the heat of said burner element.

55 8. In a stove of the class described, the combination with a casing of a unitary stove structure, said structure comprising a fuel tank, a burner element, and fuel supply connection between the tank and element, said structure being adapted to be entirely received within said casing when the stove is not in use, the casing bottom having an opening permitting positioning of said structure for operation with the burner element entirely within the casing and above 60

said opening and with the tank below said opening, means for supporting said structure in such operative position, and a plate secured to the structure between said tank and burner element and serving to close said opening when the stove is in use and to protect said tank from the heat of said burner element.

9. In a stove of the class described, the combination of a stove frame in the form 75 of a casing having an opening in its bottom and a closure plate adapted to be moved to expose said opening, of a stove structure comprising a fuel tank, a burner element, and a fuel supply connection between the tank and element, said structure being adapted to be entirely received within the walls of said casing when the stove is not in use, said opening permitting insertion therethrough of said tank to bring said structure 80 in operative position with the burner element within the casing and above said opening and with the tank below said opening, and a plate for supporting said structure in such operative position, said plate serving to close said opening and to shield said tank from the heat of the burner element when the stove is in operation.

10. In a stove of the class described, the combination of a stove frame in the form of a casing having an opening in its bottom, a closure plate for normally closing said opening but adapted to be moved to expose the opening when the stove is to be used, a fuel tank, a burner element, a controllable fuel supply connection between said tank and burner element, a wall between said tank and burner element, said tank, burner element, connection and wall being all secured together to form a unitary structure 95 adapted to be laid on its side and entirely within the casing when the stove is not in use, said opening being shaped to permit insertion therethrough of said tank to bring said structure in upright operative position with the burner element entirely within the casing and with the tank below the casing, said wall serving to close said opening and to form a heat shield for the tank when the stove is in operation.

11. In a stove of the class described, the combination of a casing having an opening in one of its walls, a unitary stove structure comprising a fuel tank and a burner element together with a fuel supply connection between the tank and element, said structure being adapted to be entirely received within said casing when the stove is not in use, said opening adapting insertion therethrough of said tank to bring said structure in operative position with the burner element entirely within the casing and said tank outside thereof, and a closure plate for said opening acting also as a heat shield for said tank.

12. In a stove of the class described, the combination of a casing, means for supporting said casing on but spaced away from a support, a fuel tank, a burner element, a fuel supply connection for connecting said tank with said burner element, means for supporting said burner element within said casing and said tank below the bottom of

the casing, said tank being adapted to be packed entirely within said casing with said burner element when the stove is closed for transportation. 10

In witness whereof, I hereunto subscribe my name this 22nd day of November A. D., 1923.

WILLIAM J. FRISBIE.
